A. G. SCHAEFER

BOBBIN CHANGING DEVICE

Filed Sept. 6, 1921

Patented Jan. 13, 1925.

UNITED STATES PATENT OFFICE.

AUGUST G. SCHAEFER, OF LACHEN, SWITZERLAND, ASSIGNOR TO THE FIRM COHEN
& SCHAEFER, WEBEREI APPARATE-FABRIK LACHEN, OF LACHEN, SWITZERLAND.

BOBBIN-CHANGING DEVICE.

Application filed September 6, 1921. Serial No. 498,697.

To all whom it may concern:

Be it known that I, AUGUST G. SCHAEFER, a citizen of the Republic of Germany, residing at Lachen, Canton Schwyz, Switzerland, have invented certain new and useful Improvements in Bobbin-Changing Devices, of which the following is a specification, reference being had therein to the accompanying drawing.

10 This invention relates to a device for automatically replenishing the weft bobbins of power looms. On the weft thread being exhausted, the empty bobbin is automatically removed from the shuttle without first stopping the loom, and at the same time a new full bobbin is introduced.

The bobbin changing devices of this kind hitherto used, are utilized almost throughout only on new looms which are built as 20 special looms, whilst such devices as additional devices or attachments for old looms, have found only a very limited application in the industry on account of their cumbersome construction and of their imperfect 25 action. The present invention can be fitted to new as well as to old looms without substantially modifying their construction.

The device according to the invention for automatic exchange of weft bobbins in 30 power looms in which a lever device conveys a bobbin from a magazine into a shuttle, an empty bobbin contained in the shuttle being simultaneously pushed out, is characterized by the bobbin magazine being 35 rotatable about a fixed point of the loom and by a part of the lever device, formed into a hammer, being mounted rotatably relatively to the other part, and by the bobbin entering the shuttle before the batten 40 has reached its front dead centre position, the bobbin magazine and the hammer being turned during the remainder of the movement of the batten to the said dead centre position.

45 A construction according to the invention is illustrated by way of example in the accompanying drawing in which:

Fig. 1 shows the device seen from the side in the position of rest;

50 Fig. 2 is a similar view of the device during the exchange,

Fig. 3 shows the device when the batten is in the front dead centre position and with the bobbins exchanged, and

Fig. 4 is a partial plan in section on line IV—IV of Fig. 3.

Fig. 5 illustrates in elevation part of a loom fitted with the device according to the invention.

The change device illustrated comprises 60 a magazine *c* loosely mounted on pivot pins *b* on the frame *a*; the said magazine is controlled by a tension spring *d* which tends to turn it in the anti-clockwise direction. The position of the magazine *c* is limited 65 by a stop *c'* which strikes against a counter-stop *c''* on the frame *a*. To the magazine *c*, near the weft bobbin *o* is rigidly secured one end of a spring blade *e* so that it can be forced from its position of rest against 70 the said bobbin, away from the same, and each time tends to return to said position. The said blade forms at the same time a closing lip for the magazine *c* and keeps the lowest bobbin *o* in its correct position 75 in the magazine. The hammer *f* connected to the long arm of the lever *g* is rotatable about a pin *g'* and so arranged that it can be turned from its position of rest only 80 towards the side facing the magazine *c*, and in the position shown in Fig. 1, in which it is turned away from the magazine, it is held by a tension spring *h* which pulls a projection on the hammer against stop tappets *i* on the lever *g*. The lever *g* is 85 held in its position of rest (Fig. 1) by the action of a spring *t*, the position of rest being determined by a boss *u* (Fig. 4) at the end of the long arm of the lever *g* which engages with a recess *x* of the 90 magazine.

To the short arm of the lever *g* is pivoted a plate *m* which rests on a cam lever *l* which is secured to a cross bar *k* which can be turned by a weft fork or a weft 95 feeler. The lay or batten *q* is provided with a finger or projection *n* which when the plate *m* is raised, comes into engagement with the same.

The batten *q* is reciprocated in a known 100 manner for instance by means of a crank *v* imparting a swinging motion to a

lever w to which the batten q is secured (Fig. 5).

The working of the device described is as follows:

5 The exchange of a weft bobbin takes place, as is well known, as soon as the shuttle p is on the opposite side to the weft fork or to the weft feeler, on which side is also arranged the magazine c . The cross bar k which on the one side is connected to the weft fork or to a weft feeler, and on the other side to the cam lever l , raises the latter upwards, and the plate m on the same is brought within reach of the finger or projection n . Owing to the advance of the batten, the finger or projection n will act on the plate m , owing to which the lever g will be turned about the pin g' ; the hammer f executes at the same time a movement downward and forces the lowest bobbin o from the magazine past the closing lip e , so far down that the empty bobbin is removed from the shuttle p and drops through the opening r in the batten block q , and the full bobbin can spring into the shuttle.

At the moment when the hammer f begins to move, the batten has not yet reached its front dead centre position. The shuttle p 30 has however already assumed its position of rest in the shuttle box under the bobbin o in the magazine c . The bobbin o is forced by the moving hammer f between the bottom end of the back wall of the magazine c , 35 forming the closing lip c^2 , and the blade e forming the second closing lip, only the blade or tongue e yielding however and its lower portion forced away from the magazine (Fig. 2); as the magazine c owing to 40 the more powerful tension spring d , remains in the position of rest. The hammer f does not follow the new bobbin o to its final position in the shuttle p ; as soon as it has moved down a little beyond the position 45 shown in Fig. 2, and before it has reached the lowest position in Fig. 3, the bobbin automatically springs into the clamping spring provided in the shuttle p . The exchanging of bobbins is therefore finished before the batten has arrived in its dead 50 centre position. The batten q continuing to advance, the stop s thereon strikes against the blade e which is pressed against the hammer f whereby the magazine c as well 55 as the hammer, which continues to swing towards the magazine, are turned in the clockwise direction (see Fig. 3) and lifted off the respective stops c' , c^3 and i .

The fact that the exchange of the bobbin 60 is finished before the batten has arrived at its dead centre position is of considerable advantage as it ensures a safer exchange of the bobbin than is the case when the exchange has to take place during the short 65 moment in which the batten remains in its

dead centre position. Further, the feature that the magazine and the hammer are adapted to carry out turning movements against a yielding resistance, prevents destruction of the bobbin changing device 70 should a foreign body lodge itself between the shuttle and the bobbin to be exchanged, or if the latter is not in the proper position for the exchange.

I claim:

1. A weft replenishing mechanism for looms, comprising in combination, a bobbin magazine adapted to swing about a fixed point of the loom, a lever mechanism adapted to rotate about another fixed point of the loom, a transerrer rotatably mounted on said lever mechanism to force a bobbin into the active shuttle by the rotating movement of said lever mechanism, means operatively connected to the loom batten and co-operating with said lever mechanism to cause said rotating movement of said lever mechanism when the batten moves toward its dead-centre position, and means adapted to displace the bobbin magazine and the transerrer relatively to said lever mechanism by causing the bobbin magazine and the transerrer to swing when the exchange of a bobbin is finished and during the further movement of the loom batten into its dead-centre position.

2. In a power loom, in combination, a bobbin magazine adapted to turn about a fixed point of the loom in one direction from its position of rest, a spring operatively connected to said magazine for counteracting said turning movement, a lever device adapted to rotate about a fixed point of the loom, a hammer forming part of said device and adapted to be rotated in one direction of said device and to force a bobbin from said magazine into a shuttle upon a turning motion of said lever device, a spring operatively connected to said hammer for counteracting said relative rotating motion, a batten, a stop on said batten adapted to co-operate with said lever means for automatically causing said turning motion of said lever device, a further stop on said batten adapted to cause a turning motion of the magazine and the hammer relatively to said lever against the action of said springs during the movement of the batten into its dead centre position after the exchange of the bobbin has been effected.

3. In a power loom, in combination, a bobbin magazine adapted to oscillate about a fixed point of the loom, one end wall of said magazine forming a closing lip for said magazine, another lip constituted by a plate spring fixed to said magazine, a lever device adapted to rotate about a fixed point of the loom, a hammer forming part of and rotatably mounted relatively to said device and adapted to force a bobbin

from said magazine into a shuttle upon a turning motion of said lever device, a batten, means provided on said batten and adapted to cooperate with said lever means for automatically causing said turning motion, further means on said batten adapted to cooperate with said plate

spring to cause a turning motion of the magazine and the hammer relatively to said lever device during the movement of the batten into its dead centre position after the exchange of the bobbin has been effected. 10

In testimony whereof I affix my signature.

AUGUST G. SCHAEFER.
